ROOF OR WALL HATCH

Joseph M. Malik, Fred A. Malik, and Harry S. McDonald, all of P.O. Box 751, Toccoa, Ga.
Filed Feb. 10, 1959, Ser. No. 792,335
3 Claims. (Cl. 268—102)

The present invention generally relates to a hatch in a roof or wall of a building structure and more particularly to a cover for such a hatch so that the cover will be retained in closed position by a locking device which is releasable by operation of a suitable operating rod so that the hatch cover may be released and opened simultaneously by a single movement of an operating rod or the like so that access may be had to the interior of the building structure for purposes of conveying material into the building structure or removing the same.

In building structures such as grain bins, tanks, or the like, there is normally provided an outside opening in the roof or side wall for the purpose of filling or excavating the same by use of an auger conveyor, air conveyor, shovel, belt conveyor or any other mechanical or manual manner. These openings are provided with covers which must necessarily be held in position to provide a rain-proof structure and also the cover must be held in position against the action of the wind. A further necessity is the provision of the cover which may be easily removed when it is desired. Therefore, it is the primary object of the present invention to provide a hatch cover which will be securely and positively locked upon application of forces on the hatch cover itself but which may be easily opened by application of force to an operating linkage by employing an operating rod or the like.

A further object of the present invention is to provide a hatch in accordance with the preceding objects which is extremely simple in construction, easy to use, easy to install, effective in operation and relatively inexpensive to manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the hatch of the present invention;

FIGURE 2 is a side elevation illustrating two positions of the hatch and operating linkage including an intermediate position and a fully opened position;

FIGURE 3 is a sectional view taken substantially upon a plane passing along section line 3—3 of FIGURE 2.

FIGURE 4 is a side elevation of the structure;

FIGURE 5 is a plan sectional view taken substantially upon a plane passing along section line 5—5 of FIGURE 2 illustrating the structural relationship of the component parts; and

FIGURE 6 is an exploded group perspective view illustrating the linkage mechanism for operating the hatch cover.

Referring now specifically to the drawings, the numeral 10 generally designates the hatch of the present invention which includes an enlarged panel 12 which may be mounted on the roof in any suitable manner and which may be a part of the roof or the part of the wall of a building structure. The panel 12 is constructed to fit the material of the roof. For example, panel 12 would have roofing or it may be corrugated or flat to fit built up roofs, paper, composition or like materials. The panel 12 is provided with an enlarged opening 14 defined by an upstanding peripheral flange 16 which may

2

be of any suitable construction but which is preferably of square or rectangular configuration. The panel 12 and flange 16 are welded thereby eliminating the possibility of leakage occurring at the juncture between panel 12 and flange 16 which is an important feature. A closure plate 18 is provided for the flange 16 and the coverplate 18 is provided with a depending flange 20 telescopic over the upper end of the flange 16 thereby providing a closure for the enlarged opening 14.

The cover 18 is hingedly attached to the flange 16 by a pair of hinge brackets 22 each having a pair of hinge barrels 24 thereon for receiving a hinge barrel 26 therebetween. The hinge barrel 26 is formed on the lower edge of the flange 20 and a hinge pin 28 retains the hinge barrel 24 and 26 in assembled relation thereby hingedly attaching the cover to the flange 16.

At the edges of the cover 18 adjacent the hinges, there is provided a generally rectangular depending and rearwardly extending plate 30 which has an inclined forward edge 32 and an aperture 34 at the lower outer corner. The plate 30 is secured to the cover 18 and the flange 20 by any suitable means such as welding or the like.

Hingedly connected to the lower rear corner of the plate 30 is a link 36 having an aperture 38 in one end thereof receiving a hinge pin 40 which also extends through the apertures 34 thereby hingedly attaching the link 36 to the plate 30.

The flange 16 is provided with a projecting stud 42 forwardly of the forward end of the plate 30 and an elongated operating lever 44 is hingedly attached to the stud 42 by a fastening bolt 46 which is in the form of a pivot bolt. The upper end of the lever 44 extends upwardly and generally towards the plate 30 and is provided with an opening 48 in the upper end thereof for attachment to an operating rod or the like 50. Rigidly attached to the lever 44 adjacent the lower end thereof is an offset arm 52 which connects to the free end of the link 36 by a pivot pin 54 which will pivotally and slidably interconnect the adjacent ends of the arm 52 and link 36 so that the arm and link may move from the position illustrated in FIGURE 1 to and from the positions illustrated in FIGURE 2.

For preventing forces applied to the cover 18 from raising the cover 18, there is provided a stop lug 56 secured to the panel 12 so that the free end of the link 36 will engage the same when the link 36 is in its lower position when the cover 18 is closed. This condition is illustrated in FIGURE 1 with the free end of the link 36 abutting the stop lug 56. In view of the spaced relation between the point of pivotal connection of the link 36 to the plate 30 and the pivot axis formed by the hinge pins 28 for the cover, any attempt to raise the cover will cause movement of the link 36 towards the lug 56. Since such movement is precluded, the cover, of course cannot be opened. The only way the cover can be opened is by moving the operating lever 44 away from the plate 30 which will swing the arm 52 upwardly thus lifting the link 36 upwardly away from the lug 56 so that the free end of the link 36 will move from behind the lug 56 with subsequent movement of the arm 52 causing pivoting movement of the cover 18 to an open position due to spacing between the pivotal point of connection between the link 36 and plate 30 and the hinge pins 28.

Thus, with the present invention, the cover 18 is normally locked in a closed position to prevent opening thereof until such time as the operating lever 44 is activated. By providing a rigid operating rod 50, the cover 18 may be both raised and closed and locked from a position remote from the hatch thus facilitating the opening and closing and locking thereof.

The foregoing is considered as illustrative only of the

principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A hatch for a building structure comprising an enlarged panel having an upstanding peripheral wall defining an opening, a cover for the free edge of said wall, means hingedly connecting the cover to the wall, a link connected to said cover in spaced relation to the hinge axis of the cover, an abutment stationarily mounted on said panel and disposed in the path of movement of the free end of the link for preventing longitudinal movement of the link when the free end of the link is in engagement with the panel thereby preventing pivotal movement of the cover towards an open position until the free end of the link is elevated, and means for raising the free end of said link, said raising means including a linkage mechanism having an elongated operating member for raising the link from a remote position and for applying tension to the link for pivoting the cover to an open position, said linkage mechanism including a substantially L-shaped member having the apex thereof pivoted to the wall, one leg of said L-shaped member being defined by the elongated operating member, the other leg having the free end thereof pivotally and slidably attached to the link adjacent the free end thereof and the other end thereof rigidly attached to said elongated operating member, whereby initial movement of the operating member will effect lifting movement of the link out of engagement with the abutment and subsequent

movement of the member will cause pivotal movement of the cover about the axis of pivotal movement thereof due to the spacing between the axis of pivotal movement of the cover and the point of attachment of the link to the cover.

2. A gravity closure for an opening in a horizontal panel comprising a closure member pivotally supported along one edge thereof for swinging movement in a vertical plane, an arm pivotally connected to said member in spaced relation to the pivotal axis for free swinging movement in a vertical plane, said horizontal panel limiting the downward movement of the free end of said arm and providing a sliding surface therefor, a vertical stop lug mounted on the panel and disposed in the path of movement of the free end of the arm when the arm is engaged with the panel thereby preventing opening movement of the closure member without first moving the free end of the arm above said stop lug, and bellcrank means connected to the arm for raising the arm out of engagement with the stop lug.

3. The structure as defined in claim 2 wherein said last named means includes a generally L-shaped lever pivotally supported at the apex thereof, the free end of one leg of said lever being pivotally and slidably connected to the arm in spaced relation to the free end thereof for initially lifting the arm free of the lug without exerting longitudinal force thereon and then exerting longitudinal force thereon for opening the closure member.
